UNITED STATES PATENT OFFICE.

JOHN ARTHUR ROBERTS, OF LIVERPOOL, ENGLAND, ASSIGNOR TO UNITED ALKALI COMPANY LIMITED, OF LIVERPOOL, ENGLAND.

PERMANENT WAY OF RAILWAYS AND TRAMWAYS.

1,307,880.

Specification of Letters Patent. Patented June 24, 1919.

Application filed September 13, 1918. Serial No. 253,903.

To all whom it may concern:

Be it known that I, JOHN ARTHUR ROBERTS, a subject of the King of Great Britain, residing at Cunard Building, Liverpool, in the county of Lancaster, England, have invented new and useful Improvements in the Permanent Way of Railways and Tramways, of which the following is a specification.

10 In concrete railway and tramway sleepers the attachment thereto of the ordinary chair presents great difficulties and objections, weakening of the concrete sleeper resulting if the chair be attached to wood, or metal 15 members secured to the sleeper, while bolt fastenings cast in the concrete sleeper work loose in use and do not permit adjustment of the chairs to the rail gage.

This invention has for its object to provide 20 sleepers and chairs which are free from such difficulties and objections the sleepers and chairs being connected together without the use of spikes, bolts, screws, trenails, or other usual fastenings, and without weakening 25 of the sleepers by their being pierced, or cut, after formation, while firm and secure connection of the chairs, or the main part of the chairs, to the sleepers is secured; the chairs, or main part of the chairs, being 30 practically integral with the sleepers. The invention also provides the chairs with easily renewable means acting as resilient rail supports, and means for ready adjustment of the chairs and rails to suit the gage 35 of the track.

According to this invention, each chair, or a portion, or portions, thereof, is, or are made practically integral with a sleeper of concrete, reinforced concrete, or the like, 40 (which I will refer to as concrete herein-after and in the claims) preferably in such manner that the chair is composed of at least two portions of which one portion is fixed in, or is practically integral with, the 45 sleeper, while the other portion is movable.

The fixed portion of the chair is internally large enough to allow the rail to be dropped in and removed readily, while the rail is anchored in position by the other portion of 50 the chair, rigid attachment being secured by a wooden, or other suitable member, or wedge.

The fixed portion of the chair is provided, with one, or more than one, projection to 55 give satisfactory hold in, or adhesion to, the

100 sleeper, and these may engage reinforcing material in the concrete.

The movable portion of the chair is of horn-like form and is placed within the trough formed by the fixed portion of the 105 chair, one part being opposed to one side of, the rail, and a horizontal part extending under the rail.

Cushioning devices are provided to cushion the hammer shocks from traffic passing over the rails and packing pieces are inserted in the plane of contact between the portions of the chair to render the chairs 110 easily adjustable to the gage between the rails.

The following is a construction in accordance with this invention which will explain how the invention can be performed. We will describe it with reference to the accompanying drawing. Figure 1 is an elevation 115 of a sleeper with its two chairs. Fig. 2 shows a part of the sleeper and one chair and is drawn to a larger scale than that to which Fig. 1 is drawn. Fig. 3 shows part of a chair separately and Fig. 4 shows, 120 separately, a resilient pad for the rail. The sleeper A, is presumed to be of reinforced concrete, and the metal chairs, are made in two portions, one portion B being formed with the jaw b (between which and one side 125 of the rail C a wedge D is passed) and with an external web b² (or external webs) projecting from the said portion B and perforated if desired, as shown for instance at b³. This web, or these webs, is or are, 130 embedded in the material of the sleeper A so that the said portion B of the chair is fixed to, and held firmly in, the sleeper. The second portion B² of the chair is movable and consists of a metal piece comprising a lower 135 horizontal part b⁴ to receive the lower flange, or foot, of the rail C and a jaw b⁵ to bear against one side of the rail when the wedge 140 D is driven home.

To give resilient support to the rail a pad 145 E (or pads, or strip, or strips) of wood, or other suitable material, is placed between the inside of the fixed portion B of the chair and the lower side of the horizontal part b⁴ of the movable portion B² of the chair, on 150 the upper side of which horizontal part the lower flange, or foot, of the rail rests. The thickness, of such pad E, or strip, or the like, or the number of pads, or strips, or the like, 155 can be varied to adjust the position of the rail.

rail in the chair, the two portions of the chair being preferably made to allow of some vertical movement between them to permit of such adjustment.

- 5 If desired the two portions of the chair, instead of bearing directly against each other at the side α where the jaw of the movable portion B^2 is situated, may have packing, or shipping-strips introduced to insure an even surface between them, or liners of wood, or other suitable material, can be inserted between them for adjustment and to give any required resiliency, or cushioning, at these parts.
- 10 15 If desired, reinforcing metal of the sleeper may be made to engage the web, or webs, or equivalent projections, from the chair, or fixed portions of the chair, for example as shown at f , Fig. 2.
- 20 25 The parts in connection with the chair, (or portion of the chair) which are embedded in the concrete can be made in one with the fixed portion of the chair, or be made separately therefrom and be attached thereto. What I claim is:—
- 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710
1. The combination with a concrete railway sleeper, of a rail chair comprising a fixed part permanently secured to the sleeper and channeled to receive the rail carrier, and an independent part fitting freely within the channel of the fixed part and constituting the rail carrier, said carrier having a foot piece adapted to underlie and support the rail and an integral side piece adapted to engage one side of the rail and to bear against one side of the channel in the fixed part, together with an independent cushioning member interposed between the foot piece of the rail carrier and the bottom of the channel in the fixed part, and an independent wedging member interposed between the rail and channel on the opposite side of the latter from that against which the rail carrier bears.
2. The combination with a concrete railway sleeper, of a rail chair comprising a fixed part permanently secured to the sleeper and channeled to receive the rail carrier, and an independent part fitting freely within the channel of the fixed part and constituting the rail carrier, said carrier having a foot piece adapted to engage one side of the rail and to bear against one side of the channel in the fixed part, together with an independent cushioning member interposed between the foot piece of the rail carrier and the bottom of the channel in the fixed part, and an independent wedging member interposed between the rail and channel on the opposite side of the latter from that against which the rail carrier bears.
3. The combination with a concrete rail-way sleeper, of a rail chair comprising a fixed part permanently secured to the sleeper and channeled to receive the rail carrier, and an independent part fitting freely within the channel of the fixed part and constituting the rail carrier, said carrier having a foot piece adapted to underlie and support the rail and an integral side piece adapted to engage one side of the rail and to bear against one side of the channel in the fixed part, together with an independent cushioning member interposed between the foot piece of the rail carrier and the bottom of the channel in the fixed part, and an independent wedging member interposed between the rail and channel on the opposite side of the latter from that against which the rail carrier bears.
4. In a concrete railway sleeper, a metallic reinforcing element extending lengthwise of the sleeper transversely to the track-way, a rail chair having a fixed part embedded in the concrete of the sleeper and anchored to said transverse reinforcing element, said fixed part being channeled to receive the rail carrier, in combination with an independent part fitting freely within the channel of the fixed part and constituting said rail carrier, said carrier having a foot piece upon which the rail rests, and a side piece to engage one side of the rail, together with a cushioning element between the foot piece of the rail carrier and the bottom of the channel, and a wedge block interposed between the opposite side of the rail and the adjacent side of the channel.

In testimony whereof I have signed my name to this specification in the presence of two subscribing witnesses.

JOHN ARTHUR ROBERTS.
